(57) CLAIM

The ornamental design for a bottle, as shown and described.

DESCRIPTION

1 Claim, 12 Drawing Sheets
